18 Claims. (Cl. 48—202)

1
The present invention relates to an improved process for the efficient utilization of carbonaceous solid fuels such as coal, coke, peat and the like, and more specifically to a process for converting such materials into more valuable products including fuel gases. The invention will be fully understood from the following description and the drawing.

The drawing in FIG. 1 is a semi-diagrammatic view in sectional elevation of an apparatus for carrying out the present process and indicates the flow of the materials.

Fig. 2 is a diagrammatic flow plan showing a modification of the plan of FIG. 1.

It has been long known and appreciated that solid fuel materials such as coke, coal and the like could be converted into more valuable gaseous fuels which can be more efficiently used in this form. Producer and water gas processes are familiar to all, but neither of these processes is entirely satisfactory because the first mentioned produces a low calorific fuel, and because the second has heretofore required a discontinuous type of operation. Low temperature carbonization is also known to have many advantages, but it is difficult to carry out mechanically. The present process may be used for producing valuable fuel gas of high calorific value in a continuous manner and can be employed for carrying out the carbonization of coal at the same time in a mechanically, efficient manner.

Referring to the drawing, numeral 1 denotes the crusher or pulverizer which is employed to reduce a solid carbonaceous fuel to a finely divided form, for example, preferably of the order of below 50 mesh, or even less than 100 mesh although even small lumps say $\frac{1}{4}$ to $\frac{1}{2}$ " size may be used. For the purposes of the following description, the material will be referred to as carbonization coal, but it will be understood that other materials can be used. The finely ground coal drops from the crusher into a dispersing chamber 2, wherein it is thoroughly dispersed in a stream of superheated steam, which is added by pipe 3. The coal in the dispersion is said to be in a "fluidized" form because in this form it is capable of flowing through pipes, valves, ducts and such equipment much like a liquid, showing both static and dynamic heads. The fluidized stream is passed through pipe 4 into the lower portion of a carbonization chamber 5 which is in the form of a cylinder fitted at its lower end with a conical base 6. A grid or screen is located in the lower portion of the chamber conveniently at the place where the cone and cylinder unite.

2
An elongated vertical pipe 1, preferably opening above the grid or screen, is provided to carry a fluidized stream of solids from the carbonization chamber 5 and the stream is then conducted by the vertical pipe 8 into a combustion chamber 9, which is similar to chamber 5. Air is added to the withdrawn stream of the fluidized solid at 10 and causes the flow of the stream, as will be explained below, up into the chamber 9 where rapid combustion takes place. Additional air may be added to the chamber by pipe 8'.

A discharge pipe 11 is provided to take a stream of the fluidized solid material from the combustion chamber 9 and discharges it into chamber 5 so that the highly heated material from the combustion chamber 9, which is at a temperature of say 1800 to 2400° F., is continuously recycled to the carbonization chamber 5. This chamber is at the usual carbonizing temperature of say 500 to 1200° F. and the preheat and heat of carbonization is thus substantially completely furnished by heat supplied from the combustion chamber.

Vapors are withdrawn from the carbonization chamber 5 by a pipe 12 through cooler 13 and thence to any suitable means for recovery of the coal distillation products. Cooler 13 may be of the indirect type shown or the direct type, as desired. The recovery system (not shown) need not be described in detail because such systems are well known in the art, but should provide means for segregating the dust, tar, light oils, ammonia and fuel gas.

Combustion gases are taken from the chamber 9 by a pipe 14 which leads to a dust separator 15 and to a waste heat boiler 16 for the steam generation. The separated dust may be returned to the chamber 9 by a pipe 17.

Pipe 11', which is shown as a branch of pipe 11, is provided to draw off a portion of the highly heated fluidized contents of chamber 9 and to conduct it to a gas generator 18. This generator is shown as a vertical cylindrical vessel with a conical base, similar to chambers 5 and 8 described above, and it is preferably provided with a screen at its lower portion to act as a distributor. The fluidized solid stream is discharged into the chamber, preferably below the screen as described above and super-heated steam is added by a pipe 19. The generator is maintained at a temperature between about 1400 and 2000° F., suitable for the rapid reaction of carbon and steam to produce water gas by the well known reaction.

Gas is withdrawn continuously by a pipe 20 to a dust separator 21 and to a cooler 22. There-

after the gas may be treated in any usual manner for the removal of sulfur or other impurities, in equipment not shown, making it suitable for use as city gas or otherwise. If desired, the whole or a portion of the gas resulting from coal carbonization may be admixed with the water gas.

A fluidized stream of solids which is now largely free from carbon is withdrawn by pipe 23 from the gas generator 18 and a portion of this ash may be returned to carbonization chamber 5 in any suitable manner, for example through line 30. The solids can be discharged into the chamber 24 which is blown with steam admitted by pipe 25 and is then withdrawn by pipe 19 in a highly superheated condition required for the generation of the water gas. A portion of the fluidized solid is taken from the superheating chamber 24 by a pipe 26 and may be returned to pipe 8 for recirculation to the combustion chamber 9. A small portion is discharged at 27 to prevent accumulation in the system.

The system described above is a very flexible one, capable of many modes of operation. In it there are three main chambers or zones; the first for carbonization, the second for combustion and the third for water gas generation, but all three need not be used simultaneously. In any case, the combustion zone is operated at the most elevated temperature and is used to generate high temperature heat which is utilized for gas generation either by the carbonization of the charge or by water gas generation, which processes are operated at lower temperatures. Heat is carried from the combustion chamber to the gas generation chambers by the continuously flowing streams of fluidized solid. Thus the process is made fully continuous.

If coal is used as the raw material, it is preferably fed directly to the carbonization chamber and heat for the carbonization is supplied by a stream of highly heated carbon flowing continuously from the combustion chamber through the pipe 11 and discharging into the chamber 5. The temperature is capable of very careful regulation and control and is distributed rapidly through the fluidized mass in the carbonization chamber because of the high degree of agitation maintained therein. Chamber 5 is sufficiently large to permit the complete carbonization very rapidly and the solids removed by pipe 7 are substantially free of volatile materials and are capable of rapid combustion with air in the combustion chamber 9. The process may be operated without the water gas generation step by closing a valve in pipe 11'. If desired, an inert material such as sand may be added to the coal and circulated through the chambers 5 and 9 and the associated pipes 7, 8 and 11, so as to provide a larger volume of heat carrying solid material, but it is not required as the ash content of the coal may be allowed to accumulate and thus furnish any desired amount of inert solid. High ash coals may thus be employed in the process.

It is important in this operation not to reach a temperature such that the solid is caused to sinter or melt, and if the ash content of the coal employed has a tendency in this direction, additional materials such as lime, magnesia and the like may be added to raise the melting point of the ash so that the operation may be conducted efficiently, even where the ash is of relatively low melting point.

It is desirable in most cases to operate the water gas generator along with the carbonizer as described. In most cases there is heat available

in the combustion of the solid involatile portion of the coal in excess of that required for the carbonization reaction and the gas produced with the excess carbon in this manner is therefore of low cost.

It will be understood that the present process may be operated using coke instead of a carbonization coal as the raw material. In this instance, of course, there is no carbonization. The coke dust will be fed directly into pipe 8 and the valves in pipes 4 and 11 will be closed. In this case the fluidized stream of coke is supplied to pipe 8 through the pipe 8' into chamber 8, thence by pipe 11' into chambers 18 and 24. The addition of an inert heat carrier is of particular value in this operation, especially in starting up. At such time oil is introduced and burned in 9 until the ignition temperature of the coke is reached.

The apparatus of the present process is all constructed for operation at low pressure, but high temperatures are required, especially in the combustion zone and in the associated pipes. The equipment should be lined with high temperature tile or brick and it is found that there need be little wear if the velocity of the fluidized streams is kept down in the range of 25 to 75 feet per second. The operation of the reaction zones is smooth and proceeds without difficulty. The upward gas velocity should be of the order of 0.5 to 6 feet per second, where the solid is say 50 to 200 mesh, and progressively higher with larger sizes say 10 to 20 feet per second with lumps of $\frac{1}{4}$ to $\frac{1}{2}$ ". These velocities are sufficient to prevent the settling of the solid into compact masses and the reactions occur very rapidly while carried out when the solid is in a fluidized condition. Moreover, as indicated before, temperature control is extremely accurate.

The velocity of the gas required for maintaining the fluidized condition varies somewhat with the nature and size of the solid particles and on the particular fluidizing gas, but in general the variation is not wide and the minimum amount is of the order of 0.02-0.07 cubic feet per pound. When fluidizing with such a small amount of gas, a very dense suspension or stream results and the only effect of adding additional gas to the fluidized stream is the reduction of the density and the suspension. Advantage is taken of this property of the fluidized stream in order to effect the flow of the material from zone to zone. Thus the stream is caused to flow down the pipe 7 and up the pipe 8 by the addition of air at the point 10. The density of the fluidized stream in the pipe 7 is much greater than in the pipe 8 and a pressure differential is thus generated, which is equal to the product of the height of the column in pipe 7 multiplied by the density therein, minus the product height of the column 8 multiplied by the density of the stream flowing therein. The equipment must be carefully designed throughout so that the pressure differential is sufficient to overcome the loss due to friction. Small amounts of gas should be added to pipes and chambers at various points so as to maintain the fluidization. This is particularly important where a fluidized stream is flowing downwardly through a pipe or chamber.

In Fig. 2 there is a flow plan illustrating a method which is particularly applicable to the working up of solid carbonaceous fuel materials such as are disclosed in Fig. 1, particularly coal, peat, shale, tar sands and the like. The apparatus employed is closely similar to that shown in

Fig. 1, but the flow plan herein contained is somewhat more complete.

The raw material in finely divided form enters at 30, passing directly to the low temperature carbonization step indicated at 31. Distillation products are removed from 31 and are separated into gaseous and liquid products in the separation equipment indicated generally at 32.

The coky residue produced as a result of the carbonization is conducted to the combustion stage of the process indicated at 33 where air is also introduced. The stack gases are taken off at 34 and the hot residue at 35. A portion of this residue is returned to the carbonization stage 31 as indicated by the line 36 in order to carry heat for carbonization, as explained previously, and the second portion of this carbonaceous residue is conducted to the water-gas generation stage indicated at 37. Steam is added at 38 and ash constituents of the original fuel are collected and drawn off at 39. The gas, which is largely CO and hydrogen, is taken off at 40 and a portion of this may be drawn off for heating purposes at 41. To the remainder of the gas an additional quantity of steam is added at 42 and the mixture is passed through a catalytic conversion step wherein carbon monoxide is converted with steam to carbon dioxide.

The gas which remains is compressed at 44 and carbon dioxide is separated at 45. The remaining gas, which is substantially pure hydrogen, is then employed for the hydrogenation of the liquid distillation products produced from the original carbonization. This is accomplished in the hydrogenation step indicated at 46.

It will be understood that the carbonization, the combustion and the water-gas generation stages are conducted just as indicated in the previous description of Fig. 1, that is to say while the solid material is in a fluidized condition. The conversion of the CO to CO₂ and hydrogen by means of steam is preferably effected catalytically, using as a catalyst iron oxide or iron oxide promoted with chromium and similar materials which are well known in the art. The conversion is effected at a temperature of the order of 850° F. and low pressure is ordinarily employed.

The hydrogenation step may be any one of a number of different types which are well known in the art. For example, it may be carried out under mild hydrogenation conditions, that is to say at relatively low temperatures and pressures so that the hydrogen does little more than to effect a purification by removal of sulfur, nitrogen and similar elements. On the other hand, the hydrogenation may be carried out under destructive conditions, that is to say, at pressures above 20 atmospheres and preferably at about 200 atmospheres and at temperature say from 700 to 1100° F. In this way the tarry materials are converted fully into lower boiling liquids rich in hydrogen. In these various hydrogenation procedures, the preferred catalysts are of the sulfur immune type, especially those containing metals, oxides or sulfides of the 6th group of the periodic table, either alone or in admixture with each other or with difficultly reducible oxides such as alumina, zirconia, magnesia or lime. More readily reducible oxides such as zinc oxide can also be added to the catalyst mixtures.

The present process is thus capable of carbonizing coal and producing a high quality fuel gas continuously. The advantages will be fully understood by those skilled in the art.

Reference is made to the copending Roetheli application Serial No. 609,662, filed August 8, 1945, and the now abandoned Roetheli and Hemminger application Serial No. 630,518, filed November 23, 1945, which applications disclose and claim specific embodiments of the invention disclosed herein.

I claim:

1. The continuous process of carbonizing and gasifying finely divided solid carbonaceous material while said material is in a fluidized state, which comprises continuously charging a finely divided fuel and steam into a fluidized mass of previously carbonized finely divided solids at a carbonization temperature in a carbonizing zone so that the thus-mixed solids are in a fluidized state therein, thereby carbonizing said fuel, continuously circulating the hot carbonized solids from said zone to a separate combustion zone in which they are fluidized along with previously carbonized fuel, burning some of the fluidized solids in the said combustion zone by blasting them continuously with a combustion supporting fluid thereby heating them to a gas making temperature, continuously withdrawing hot solids from said combustion zone, charging them while at a gas making temperature into a separate gas generating zone in which they are also fluidized, blasting them in the latter zone with steam to generate combustible gas, continuously withdrawing a solid residue from said gas generating zone and returning at least a portion of it continuously to said combustion zone to be reheated, recirculating a portion of the said hot carbonized fuel from said combustion zone to said carbonizing zone, removing the volatile products of carbonization from said carbonizing zone, and separately removing the said combustible gas from said gas generating zone.

2. The process of claim 1 in which at least a portion of said residue is returned to said carbonizing zone.

3. The continuous process of carbonizing and gasifying finely divided solid carbonaceous materials, which comprises continuously charging a stream of finely divided fuel dispersed in steam into a fluidized bed of hot previously carbonized fuel in a carbonizing zone thereby carbonizing said finely divided fuel in said fluidized bed, heating a separately fluidized mass of carbonized, finely divided fuel in a separate heating zone to a gas making temperature by blasting it with a combustion supporting fluid and discharging gaseous products of combustion, generating combustible gas by passing steam through a separate, fluidized mass of finely divided carbonized fuel in a gas generating zone while it is at a gas making temperature, withdrawing and recovering the gas thus made, separately withdrawing the volatile products of carbonization from said carbonizing zone and withdrawing solid residue from said gas generating zone, substantially continuously circulating hot carbonized fuel from said heating zone to said carbonizing zone, circulating carbonized fuel from said carbonizing zone to said heating zone and circulating hot carbonized fuel from said heating zone to said gas generating zone whereby the heat for carbonization and gasification is largely generated in said separate heating zone.

4. The process of claim 3 in which at least a portion of said residue is circulated to said carbonizing zone.

5. An improved process for utilizing solid carbonaceous materials which comprises continu-

ously feeding fluidizable, finely divided, carbonizable solids into a carbonization zone and forming a fluidized mass of solids therein, withdrawing therefrom vaporous carbonization products and a fluidized stream of finely divided, solid, carbon-containing carbonization residue, gasifying a portion of the carbon of said residue while the latter is in the form of a fluidized mass of solids by a water gas reaction with steam in a gas generation zone, burning another portion of the carbon of said residue while the latter is in the form of a fluidized mass of solids by a reaction with a combustion-supporting gas in a separate combustion zone to generate heat, heating fluidized solids in said combustion zone, contacting solids so heated with said solids undergoing said water gas reaction to supply heat required by said water gas reaction, returning solids highly heated in said combustion zone to said carbonization zone to supply heat required therein, and returning solid residue from said gas generation zone to said combustion zone.

6. An improved process for utilizing solid carbonaceous materials comprising continuously feeding fluidizable finely powdered carbonaceous solids containing volatile constituents into a carbonization zone and forming a fluidized mass of solids therein, withdrawing therefrom vaporous carbonization products and a fluidized stream of finely divided carbonization residue, subjecting a portion of said residue while in the form of a fluidized mass of solids to a water gas reaction with steam in a separate gasification zone, subjecting a portion of said residue while in the form of a fluidized mass of solids to combustion in a separate gasification zone with a combustion-supporting gas to generate heat, heating fluidized solids by said heat of combustion, contacting solids so heated with said solids undergoing said water gas reaction to supply heat required by said water gas reaction, and returning solid powdered residue highly heated by the heat of said combustion to the carbonization zone to supply at least a portion of the heat required in said carbonization zone.

7. An improved process for utilizing solid carbonizable fuel materials comprising continuously feeding fluidizable, finely divided carbonaceous solids containing volatile constituents into a carbonization zone and forming a fluidized mass of solids therein, withdrawing vaporous carbonization products therefrom, separately withdrawing a fluidized stream of finely divided carbonization residue, passing the same into a combustion zone and forming a fluidized mass of solids therein, burning a portion of the carbon therein while in the form of a fluidized mass of solids whereby the remainder is raised to a high temperature, passing a stream of the highly heated solid from the combustion zone to the carbonization zone whereby heat for carbonization is supplied, passing a second stream from the combustion zone to a gas-producing zone and forming a mass of fluidized solids therein, adding steam to the gas producing zone whereby water gas is generated from the hot fluidized carbonaceous material while in a fluidized form, withdrawing the gas so produced, withdrawing a solid residue from said gas producing zone, and returning at least a portion of it to said combustion zone to be reheated.

8. A process according to claim 7 in which a portion of the solids withdrawn from said gas producing zone is returned to the carbonization zone.

9. A process according to claim 7 in which inert mineral matter is charged to the combustion zone as a heat carrier.

10. A process according to claim 7 in which material capable of raising the melting point of the ash is charged to the process.

11. An improved process for utilizing solid carbonaceous materials which comprises, continuously feeding fluidizable finely divided carbonizable solids into a carbonization zone and forming a fluidized mass of solids therein, withdrawing therefrom vaporous carbonization products and a fluidized stream of finely divided solid carbon-containing carbonization residue, gasifying a portion of the carbon of said residue while the latter is in the form of a fluidized mass of solids by an endothermic gasification reaction with a fluid gasifying medium in a gas generation zone, burning another portion of the carbon of said

15 residue while the latter is in the form of a fluidized mass of solids by a reaction with a combustion supporting gas in a separate combustion zone to generate heat, heating fluidized solids in said combustion zone, contacting solids so heated with said solids undergoing said gasification reaction to supply heat required by said gasification reaction, returning solids highly heated in said combustion zone to said carbonization zone to supply heat required therein, and returning 20 solid residue from said gas generation zone to said combustion zone.

12. An improved process for utilizing solid carbonizable fuel materials, comprising continuously feeding fluidizable finely divided carbonaceous

35 solids containing volatile constituents into a carbonization zone and forming a fluidized mass of solids therein, withdrawing vaporous carbonization products therefrom, separately withdrawing a fluidized stream of finely divided carbonization residue, passing the same into a combustion zone and forming a fluidized mass of solids therein, burning a portion of the carbon therein while in the form of a fluidized mass of solids whereby the remainder is raised to a high temperature, passing a stream of the highly heated solid from

40 the combustion zone to the carbonization zone whereby heat for carbonization is supplied, passing a second stream from the combustion zone to a gas producing zone and forming a mass of fluidized solids therein, adding superheated steam to the gas producing zone whereby water gas is generated from the hot fluidized carbonaceous material while in a fluidized form, withdrawing the gas so produced, and withdrawing a solid residue from said gas producing zone.

55 13. An improved process for utilizing solid fuel materials, comprising continuously feeding fluidizable finely divided carbonaceous solids containing volatile constituents into a carbonization zone and forming a fluidized mass of solids therein,

60 withdrawing vaporous carbonization products therefrom, separately withdrawing a fluidized stream of finely divided carbonization residue, passing the same into a combustion zone and forming a fluidized mass of solids therein, burning a portion of the carbon therein while in the form of a fluidized mass of solids whereby the remainder is raised to a high temperature, passing a stream of the highly heated solid from the combustion zone to the carbonization zone whereby

65 heat for carbonization is supplied, passing a second stream from the combustion zone to a gas producing zone and forming a mass of fluidized solids therein, adding a fluid gasifying medium to the gas producing zone whereby a fuel 70 gas is generated from the hot fluidized carbo-

naceous material while in a fluidized form, withdrawing the gas so produced and withdrawing a solid residue from said gas producing zone.

14. The process of claim 13 wherein said gasifying medium is superheated steam.

15. The process of claim 13 wherein at least a portion of said solid residue withdrawn from said gas producing zone is returned to said combustion zone to be reheated.

16. The process for recovering vaporizable products from finely divided carbonaceous solids and for producing mixtures of hydrogen and carbon monoxide which process comprises introducing incandescent finely divided carbonaceous solids into a confined contacting zone, introducing a gas comprising steam into said zone and passing said gas upwardly through said zone at a rate sufficient to maintain said solids in suspended turbulent dense phase condition, maintaining said zone under conditions for effecting conversion of a substantial amount of said steam with carbon in the carbonaceous solids for producing hydrogen and carbon monoxide, continuously separating reaction products from solids in the upper part of said zone and withdrawing gasiform reaction products from the upper part of said zone, separately removing a portion of the solids from the dense turbulent suspended phase at a point below the upper level thereof, transferring at least a portion of said removed solids to a coking zone, introducing raw finely divided carbonaceous solids into said coking zone, maintaining the solids within the coking zone in a fluidized dense turbulent phase by passing a gasiform fluid upwardly therethrough, continuously separating gasiform products from solids in the upper part of said coking zone and withdrawing said gasiform products from the upper part of said coking zone, separately withdrawing coked solids from the dense phase in said coking zone below the upper level thereof, introducing the coked solids thus removed into a heating zone, introducing a gas comprising free oxygen at a low point in said heating zone and passing it upwardly therethrough at a rate sufficient to maintain the solids in dense turbulent suspended phase in said heating zone and for heating said solids in said zone to incandescence, separating combustion products from solids in the upper part of the heating zone and removing

5

said combustion products, continuously removing a portion of the incandescent solids from said heating zone at a point below the dense phase level therein and transferring said incandescent solids to said contacting zone.

10 17. A method for converting coal which comprises establishing first, second and third beds of finely divided coke, passing a gas through each of said beds to maintain said finely divided coke in a fluidized state, the gas fed to the second bed being a combustion supporting gas and that to the third bed comprising a gasifying medium for said coke, continuously feeding coal in finely divided form to said first bed, maintaining said first bed at a carbonizing temperature, continuously feeding coke from said first bed to said second bed, subjecting said coke in said second bed to a combustion reaction in which the finely divided coke is highly heated and continuously feeding hot finely divided coke from said second bed to said first bed and said third bed.

15 18. A method according to claim 17 in which the coke gasifying medium is steam.
